CLAIM

The ornamental design for a computer screen with graphical user interface, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a front view of a computer screen with graphical user interface.

The broken lines illustrate a computer screen and form no part of the claimed design.
